Primary Examiner — T. Chase Nelson*Assistant Examiner* — Michelle E Wilson(74) *Attorney, Agent, or Firm* — St. Onge Steward Johnston & Reens LLC(57) **CLAIM**

The ornamental design for a sanitary napkin, as shown and described.

DESCRIPTION

FIG. 1 is a top plan view of a first embodiment of a sanitary napkin in accordance with the new design;

FIG. 2 is a bottom plan view thereof;

FIG. 3 is a right side elevational view thereof, the left side elevational view being a mirror image thereof;

FIG. 4 is a front elevational view thereof, the rear elevational view being a mirror image thereof;

FIG. 5 is a top plan view of a second embodiment of the sanitary napkin of FIG. 1;

FIG. 6 is a bottom plan view thereof;

FIG. 7 is a right side elevational view thereof, the left side elevational view being a mirror image thereof; and,

FIG. 8 is a front elevational view thereof, the rear elevational view being a mirror image thereof.

The broken line showing of a sanitary napkin is included for the purpose of illustrating environment and forms no part of the claimed design. The claimed design comprises printed ornamental indicia on a flat surface.

1 Claim, 8 Drawing Sheets(56)
